UNITED STATES PATENT OFFICE.

WILLIS LAWRENCE, OF YONKERS, NEW YORK.

LUBRICATOR.

1,099,608.

Specification of Letters Patent.

Patented June 9, 1914.

Application filed January 29, 1913. Serial No. 744,928.

To all whom it may concern:

Be it known that I, WILLIS LAWRENCE, a citizen of the United States, and residing in Yonkers, in the county of Westchester 5 and State of New York, have invented certain new and useful Improvements in Lubricators, of which the following is a full and clear specification.

This invention relates to lubricators which 10 are more especially intended to feed lubricating emulsions, such for example as finely divided graphite suspended in oil. Such emulsions have long been in use for lubricating bearings of various descriptions 15 which are exposed to a high degree of heat such e. g. as the piston, cylinder, and valve gear of a steam engine, the object being to provide a lubricant of sufficient body which will be capable of resisting the tendency to 20 disintegrate under the high degree of heat to which it is subjected. Certain drawbacks have been encountered in the use of emulsions of this character due to the separation by gravity which takes place between 25 the graphite and the oil in which it is suspended so that the lubricant which reaches the bearing surfaces varies in character and cannot be relied upon.

This invention also relates to lubricators 30 in which positively actuated means are employed for delivering the lubricant to the surfaces to be lubricated.

One of the objects of the present invention is to provide improved means whereby the lubricating emulsion in a reservoir 35 can be constantly agitated to insure that it is in thoroughly mixed condition at all times.

A further object is to provide improved 40 means for conveying the lubricant to its destination, said means being adapted to prevent the separation by gravity from taking place during its progress.

Another object is to provide an improved 45 operating connection between the agitating means and the pump for forcing the lubricant to the surfaces to be lubricated.

Another object is to provide the reservoir 50 of the lubricator with improved feeding means which is adapted to aid in preserving the separation by gravity.

Other and further objects will appear in the specification and be specifically pointed out in the appended claims, reference being

had to the accompanying drawings, in 55 which—

Figure 1 is a central vertical section of one embodiment of my invention, parts being shown in elevation; Fig. 2 is a section on the line II—II Fig. 1; Fig. 3 is a horizontal section corresponding to the line III—III, Fig. 1, but with one of the pump castings shown in full from above; Fig. 4 is a detail section on the line IV—IV Fig. 3.

Referring more particularly to the drawings and to the embodiment shown therein, a reservoir for lubricant is provided in the form of an upper shell or portion 1, which may be constructed of any suitable material, such as glass or metal having an annular flange 2 by means of which it is mounted upon an annular transverse wall 3 which extends around the upper edge of a central well 4 and connects said well to said upper shell or portion 1. The shell 1 is secured to the annulus 3 by means of screws 5 or other suitable fasteners. The well 4 is in the form of a hopper within the throat of which is journaled a rock shaft 6. Said rock shaft is provided with a longitudinal slot within which is mounted an agitator or blade 7, said blade being disposed to have the greater portion thereof projecting upward into the well or hopper 4 and with a depending portion below the rock shaft 6 which projects through a slot 8 (see Fig. 3) which extends longitudinally throughout a portion of the length of a cross head comprising a central hub or block 9 and trunnions 10 projecting from either end thereof, said trunnions being socketed within a pair of laterally spaced slides 11 (see Fig. 2). Said slides are reciprocably mounted in oppositely disposed recesses in the cross-head housing 12.

As shown in Fig. 1, the blade 7 is provided with a slot 13 through which extends a screw 14 which is threaded within a central hub 9 of the cross head. Each of the slides 11 is provided with T-slot 15, for the reception of the T-head 16 on the end of a plunger 17, there being one of said plungers operated by each slide 11. Each plunger 17 reciprocates within a cylinder 18 provided with an inlet port or ports 19 leading from a receptacle 20 which catches the lubricant which is fed from the reservoir through the feeding means in the manner to be presently referred

to. An outlet port 21 which is controlled by a valve 22 opens into an outlet chamber 23. Said chamber 23 communicates by way of a port 24 with a socket 25 into which the feed 5 of the lubricating pipe may be threaded. As shown best in Fig. 4, these several parts are preferably constructed in a single casing provided with a flange 26, which fits snugly against the end wall 27 of the cross head 10 housing. A suitable stuffing box for each plunger 17 may be provided by forming a protruding annulus 28 which as shown in Fig. 3 extends into a complementary recess for the reception of suitable packing.

15 Referring now more especially to Figs. 1 and 2, the reservoir for lubricant is provided with feeding means in the form of a point or dropper 29 which is threaded into the flanged upper end of the well or hopper 4. 20 Said dropping point is provided with an outlet port 30 which discharges on to the curved surface of the inner wall of the point 29, said surface being reduced downwardly in the present embodiment by having said 25 point 29 cut on the slant, in this way reducing the surface of cohesion to which the lubricant clings, to a minimum at the point of separation between said point and the lubricant. Said point 29 is suitably disposed to drop the lubricant into the receptacle 20 from whence it feeds to the cylinders 18 when the plungers 17 move to the right. In order to provide suitable and efficient means for controlling the port openings 30 35 leading to each of the points 29, a valve rod 31 provided with a needle point 32, is provided adjacent its upper end with the threaded portion 33 which is threaded in a conical split nut 34 of well known construction and operation. The shell 1 is provided above 40 with a central opening 35 for introducing a lubricant, said opening being closed by a cap 36 which may be secured thereto in any suitable manner.

45 By an inspection of the drawings, it will be seen that the discharge outlet 30 of the reservoir 1 is disposed adjacent to the path of movement of a portion of the agitator blade 7 which has the greatest scope of movement and that the agitator projects the lubricant toward said outlet 30. It will also be noticed that the discharge opening 30 is arranged below the top and above the bottom of the reservoir as a whole, which comprises the parts 1 and 4 and that the bottom wall or well 4 is contracted downwardly from said discharge outlet 30. The agitator blade 7 is made with minimum cross section adjacent the rock shaft 6 to confine breakage 50 to the agitator blade.

60 What I claim is:

1. In a lubricator, a reservoir having a bottom well enlarged upwardly, a rock shaft journaled at the bottom of said well, a blade 65 mounted on said rock shaft, said blade being

thereby adapted to be oscillated from one side to the other of said well, said reservoir being provided with an outlet above and to one side of said well, and means for conveying oil from said outlet.

2. A lubricator comprising a reservoir, an agitator disposed adjacent the bottom of said reservoir, said reservoir being provided with a transverse wall adjacent the path of movement of the upper edge of said agitator 75 and a discharge outlet opening downwardly through said transverse wall.

3. In a lubricator, a rock shaft, an agitator blade projecting from opposite sides of said shaft, a reservoir for lubricant into which the agitator blade on one side of the shaft projects, a pump connected to the agitator blade on the opposite side of said shaft, and means for feeding the lubricant from said reservoir to said pump.

4. In a lubricator, a rock shaft, an agitator blade projecting from opposite sides of said shaft, a reservoir for lubricant into which the agitator blade on one side of the shaft projects, a pump connected to the agitator blade on the opposite side of said shaft, and means for feeding the lubricant from said reservoir to said pump, said feeding means being constructed and arranged to deliver the mixed lubricant in an attenuated stream to prevent separation by gravity of said lubricant.

5. In a lubricator, a rock shaft, an agitator blade projecting from opposite sides of said shaft, a reservoir for lubricant into which the agitator blade on one side of the shaft projects, a pump connected to the agitator blade on the opposite side of said shaft, and means for feeding the lubricant from said reservoir to said pump, said blade being constructed with its least cross-sectional area and strength adjacent said rock shaft to adapt it to break at that point under abnormal loads upon the oppositely extending portions of said blade.

6. A lubricator comprising a reservoir, an agitator disposed adjacent the bottom of said reservoir, said reservoir being provided with a transverse wall adjacent the path of movement of the upper edge of said agitator and a discharge outlet opening downwardly through said transverse wall, and means connected with said discharge outlet for maintaining an attenuated outflow from said outlet.

7. In a lubricator for lubricants embodying ingredients of different specific gravities, a reservoir provided with a discharge outlet above the bottom of said reservoir, an agitator disposed within said reservoir below said outlet, said agitator being adapted to impel the heavier ingredients upwardly from the bottom of said reservoir toward said outlet, and means for driving said agitator.

8. A lubricator comprising a reservoir for lubricant, an agitator for mixed lubricants in said reservoir, and means for feeding the lubricant from said reservoir, said feeding means including a surface converging downwardly over which the lubricant flows and a valve for controlling said flow, said valve being arranged above said feeding means and adjacent to the upper edge of said agitator.

9. A lubricator comprising a reservoir for lubricants, an agitator blade in said reservoir, means for driving said blade, a pump having a piston, and a member movably supported by said piston and having power transmitting engagement with said agitator blade.

10. A lubricator comprising a reservoir for lubricant, an agitator in said reservoir, means for driving said agitator, means for feeding the agitated lubricant from said reservoir, and lubricant conveying means receiving the lubricant from said feeding means, said conveying means being operatively connected to said agitator driving means, by means of said agitator.

11. A lubricator comprising a reservoir for lubricant and a blade oscillatable about an axis adjacent the bottom of said reservoir, said reservoir being provided with feeding means arranged to draw off the lubricant adjacent the path of movement of the upper edge of said blade and to feed it in an attenuated stream therefrom.

12. In a lubricator, a reservoir for lubricant, a rock shaft journaled in said reservoir, a lubricant agitating blade carried by said rock shaft, and a lubricant pump provided with a piston or plunger operatively connected to said rock shaft by means of said blade.

13. In a lubricator, a reservoir for lubricant, a rock shaft journaled in said reservoir, a lubricant agitating blade carried by said rock shaft, and a lubricant pump provided with a piston or plunger operatively connected to said blade, said piston or plunger having a slip joint connection with said blade.

14. In a lubricator, a reservoir for lubricant, a rock shaft journaled in said reservoir, a blade carried by said rock shaft, spaced slides arranged below said rock shaft, the lower edge of said blade being operatively connected with said slides, and pistons or plungers driven by said slides.

15. In a lubricator, a reservoir for lubricant, a rock shaft, a blade carried by said rock shaft and projecting into said reservoir, said blade being provided with a portion depending below said rock shaft, a reciprocating crosshead having operative connection with said depending portion of the blade to be reciprocated thereby, and pumping means connected to said cross head.

16. The combination with a lubricator comprising a reservoir for lubricant provided with a discharge outlet and an agitator movable in said reservoir, of a pump having a piston driven by said agitator, said pump being provided with a cylinder with a receptacle disposed beneath the outlet of said reservoir, said receptacle being in open communication with said cylinder.

17. In a lubricator for lubricants embodying ingredients of different specific gravities, the combination with a reservoir comprising a relatively large upper portion and a relatively small bottom well connected thereto by a transverse wall, said transverse wall being provided with a discharge outlet, of an agitator disposed within said bottom well and below said transverse wall.

18. In a lubricator for lubricants embodying ingredients of different specific gravities, the combination with a reservoir comprising a bottom well contracted downwardly and an upper shell of larger cross sectional area than the upper portion of said well, said well and upper shell being united by an annulus within which a discharge outlet is provided and an agitator movable about an axis adjacent the bottom of said well.

WILLIS LAWRENCE.
